UNITED STATES PATENT OFFICE.

VINCENT G. APPLE, OF DAYTON, OHIO.

DYNAMO-ELECTRIC MACHINE.

1,031,316.

Specification of Letters Patent.

Patented July 2, 1912.

Application filed April 5, 1910. Serial No. 553,650.

To all whom it may concern:

Be it known that I, VINCENT G. APPLE, a citizen of the United States, residing at Dayton, in the county of Montgomery and State of Ohio, have invented certain new and useful Improvements in Dynamo-Electric Machines, of which the following is a specification.

My invention relates to improvements in dynamo electric machines, and has for its general object to improve the structure of dynamo electric machines, and especially to reduce the cost in the assemblage of the parts in the construction of such machines. Another object of my invention is to provide a machine which is not only cheaper in the operation of assemblage but which is very efficient and which, owing to the character of its structure, will remain cool during continued operation under heavy load.

Other and further objects of my invention will become apparent to persons skilled in the art from a consideration of the following description taken in conjunction with the drawings, wherein—

Figure 1 is a side elevation of my improved dynamo-electric machine, showing parts in section; Fig. 2 is a central vertical cross sectional view, with the armature removed; Fig. 3 is a view of a composite pole ring, showing the assembled pole shoes used for a quadrupolar dynamo in a separate structure; Fig. 4 is a view of a single lamina or plate, a number of which are used to constitute a pole shoe or terminal of one of the field poles of the field magnet; Fig. 5 is a view from the obverse side of the same lamina; Fig. 6 is a view of the lamina looking from above Fig. 5. Fig. 7 is an enlarged section taken on line 7—7 of Fig. 3; and Fig. 8 is an enlarged section taken on line 8—8 of Fig. 3.

In all of the views the same reference characters indicate similar parts.

For the purpose of disclosure, I have illustrated a quadrupolar dynamo, but it will become obvious, from the following description, that my invention is applicable to a dynamo of any character wherein confronting field poles are located on opposite sides of the axis of a revolving armature.

One of the salient features of my invention consists in the assembling and securing

together, in a single entity, the pole shoes of the field magnets and placing them in their proper relation within the frame of the dynamo electric machine, so that the pole shoes will register and come into contact with the proper, corresponding, field magnet. The advantage of laminating the pole shoes of the field magnet of a dynamo electric machine for the purpose of preventing loss by hysteresis and eddy currents is well known and understood. To construct the entire frame of the dynamo electric machine of thin sheets of magnetically susceptible material is expensive, and when such machines are made, in this manner, and the pole shoes become an integral part of the magnetic poles of the field magnet, such structures necessitate the winding of the field magnet coils by hand, in the spaces in which they are to be contained; this is also expensive. By the practice of my invention, I attain the advantages of a completely laminated pole face structure, attendant with low cost of production and other mechanical advantages, the field coils of my machine being held in their respective positions on the respective magnets, so that assemblage and location of the parts is easily and quickly accomplished.

10 indicates generally the frame of a dynamo electric machine, provided, in this illustrative exemplification, with four magnetic poles 11, 12, 13, and 14. The metal intermediate of the poles, together with the poles, constitute a dust proof casing, in which the armature is rotated. At one end of the casing, I provide a bearing 16, for the armature shaft, 17. At this end, the commutator of the machine is located, and is normally inclosed by the hinged cover, 18, secured on each side of the frame by a separable hinge 19, having a removable pintle or pin, 20. When the pins, 20, on either side of the casing are removed, the top 18 may be swung on the oppositely disposed hinge, and when both pins are in place, the top is firmly held in proper relation. Therefore, to obtain access to the commutator, it is only necessary to remove one of the pins 20. The rear end of the casing, 10, is provided with a large opening, surrounded by flanges, 21, through which the pole shoe structure and the armature may

be inserted when placing the same within the casing. A bearing support, in the shape of a disk, 22, fits firmly into this opening and provides a bearing for the pulley end 5 of the shaft, 17.

Field coils, 11', 12', 13', and 14', may be wound upon forms, suitably insulated, and slipped over the ends of the respective inwardly projecting pole pieces within the 10 casing. These field coils may be held in place by means of the pole shoe ring, which is inserted between the respective pole pieces and projects circumferentially beyond each of the polar ends of the magnets, affording 15 ample, firm, support for each of the field coils, and preventing them from being displaced from the respective magnet poles which they surround. The pole shoe ring is made up of a series of crescent-shaped laminae, such as shown in detail in Figs. 4 and 20 5, and indicated generally at 25. Each of the pieces 25 is perforated as at 26 for the insertion of a bolt, 27. Each of the pieces, 25, is also provided with indentations, 28 and 25 28'. These indentations or depressions are shown enlarged in Fig. 8. It is obvious that they nest one within the other when the pieces are placed on the bolts 27, and pressed together in the process of assembling them. By this means they are held in 30 register so as to provide a smooth polar surface between the rings of which they constitute a part.

The sections, 25, are punched from sheet 35 metal of proper material and highly permeable to magnetism. The perforations, as at 26, as shown in Figs. 4, 5 and 6, and the indentations or deflected portions, 28 and 28', are pressed in the sides of each of the 40 sections. To prevent magnetic and electric longitudinal continuity, the side surfaces of the pieces, 25, may be painted or coated with any suitable material well known in the art for this purpose.

45 End rings, 29 and 30, preferably of brass, or some other diamagnetic material, form a part of the frame upon which the segments 25 are to be supported. Each of the rings, 29 and 30, are perforated for the reception 50 of the bolts, 27, at as many points within their circumference as there are field poles in the dynamo. The segments, 25, are then threaded upon the bolts, 27, and the deflected indentations, 28 and 28', nest within each 55 other as shown clearly in Fig. 7, whereby they mutually hold the respective pieces, 25, and prevent them from shifting laterally or around the axis of the bolt by which they are supported.

60 One or more strengthening rings, 31, preferably of brass, to prevent the circumferential magnetic continuity, is placed intermediate of the frame rings, 29 and 30, for the purpose of affording strength to the structure. When the desirable number of seg- 65

ments, 25, have been inserted upon the respective bolts, 27, to substantially or somewhat more than equal the longitudinal extent of the pole pieces of the armature, the segments are compressed tightly together, 70 and the rods, 27, upon which they are strung are headed over at their ends, as at 32, as clearly shown in Fig. 7. By this construction, I provide a laminated pole shoe for each of the magnets of my dynamo electric 75 machine, and retain them in their proper relation with reference to the respective magnetic poles and secure them together in such manner that they are as a unit bodily removable from the dynamo.

80 Any means, such as a pin, screw, or the like, may be employed for preventing the pole shoe structure from shifting in regard to the respective poles, when placed in the proper position within the dynamo; but in 85 practice, I have found that it is sufficient merely to grind the casing to a very slight internal taper for engagement of the pole shoe structure. The unit structure of laminated pole shoes, not only adds to the efficiency of the apparatus by preventing loss due to hysteresis and consequent heat, but it is a convenient and cheap method of constructing the parts, as the inner magnetic surface, provided by the respective pole 90 shoes, is true and proper and definite in diameter, so that subsequent boring out of the pole shoe structure is unnecessary.

I have found from experience that the extension of the magnetic polar surface of the 100 field magnet accomplished by the pole shoes, contributes to the increase output of the dynamo.

105 While I have herein described in some detail the structure as applied to a dynamo electric machine, particularly to a so-called electric generator, it is obvious that it is equally applicable to an electric motor.

110 While I have herein described, in some detail, a particular embodiment of my invention, it is apparent that many changes may be made therein without departing from the invention, and within the scope of the appended claim.

115 What I claim is:

The combination, in a dynamo-electric machine having a plurality of radially disposed magnetic poles and coils around said poles, of a pole-shoe structure comprising opposite unbroken end rings of suitable diamagnetic material, a bolt passing through a perforation in each ring adjacent the center of each said magnetic pole, a series of pole-shoe laminae upon each said bolt, each lamina having deflected portions for interfitting with corresponding deflected portions of adjacent laminae to maintain the series of laminae upon each bolt in perfect alinement, and an unbroken strengthening ring of diamagnetic material, having a perforation ad- 120 125 130 135

jacent the center of each said pole to receive said bolts, said strengthening ring lying intermediate said end rings to lend support to said bolts and laminæ-series at their centers, and to provide a central continuous circular support to maintain said coils in place upon said poles, as described.

In testimony whereof I hereunto set my hand in the presence of two witnesses.

VINCENT G. APPLE.
